INK TRANSFER PAD

John A. Dondero, Brooklyn, N. Y.

Application October 24, 1936, Serial No. 107,393

1 Claim. (Cl. 91—54.5)

This invention relates to ink transfer pads. More particularly, it relates to pads used for holding and supplying inks of different types for transfer use in printing and etching.

5 Pads heretofore used for holding inks adapted for transfer in printing and impressing have the disadvantage of not having sufficient ink on the surface ready for continuous removal therefrom, with the result that when such pad is extensively used the top runs dry and a very poor transfer impression is made. The ink in the lower part of such types of pads does not travel fast enough to replenish the top for continual use. Also, in other cases the ink supplied from the pad to its 10 surface for transfer is so abundant that smudges and blotches are produced after the transfer and an impression or an etching is made.

With the above disadvantages of the prior art in view, it is one of the objects of the present invention to provide a simply and effectively constructed ink pad having its top constantly replenished with ink.

Another object of the present invention is to provide an article of manufacture of compact construction containing an easily replenished pad for supplying sufficient ink to the surface for transfer without permitting too much to be retained by the ink removing medium to cause any blurs or smudging of the ink by the medium before its use.

30 Still another object of the present invention is to provide an ink pad, which will permit fine impressions to be taken; such as, of fingerprints, hand prints, foot prints, rubber, wood, plastic or metal etchings, or of botanical and histological specimens or impressions of any other part of the body of man or animal by supplying the proper amount of removable ink material from the pad.

One further object of the present invention is to provide an ink pad for carrying sufficient 40 quantity of ink which can be supplied at a constant rate to meet the continual demand of continued use.

With the above and other objects in view, the invention generally includes a holder, and a pad having a multiplicity of novel component cooperative parts for supplying a steady stream or amount of transferable material by capillary or other action, adaptable for use in print or etching work.

50 In the drawing:

Fig. 1 is a plan view of a preferred embodiment of my invention.

Fig. 2 is an end view of Fig. 1, taken on the line 2—2 of Fig. 1.

Fig. 3 is a sectional view of Fig. 1 taken on line 3—3 of Fig. 1.

Fig. 4 is a sectional view of a modification of the embodiment shown in Fig. 1.

Fig. 5 is another sectional view of a modification of the embodiment shown in Fig. 1.

In the accompanying drawing like numerals refer to like parts throughout.

Referring to Figs. 1, 2 and 3 of the accompanying drawing, a holder 10 of any desired shape and made of any suitable material such as stainless steel or Bakelite is provided with a hinged cover 11 adapted to be swung over the holder in order to cover the same. It is to be noted that the holder may be of any convenient size as commonly used in the arts. Adapted to fit into the holder 10, is a pad 12 having a plurality of elements each of which has important cooperative functions.

The pad comprises an ink retainer or holder 13 for inking materials and the like. Said retainer may be of any material for retaining liquids or inks either by absorption or adsorption, or it may be an open retainer 14 as shown in Fig. 5. The retainer also extends substantially the length of the pad holder 10 and is adapted to hold any type of ink whether colored or colorless. It has been found that felt, woven fabrics, cotton and sponge rubber are effective in retaining the ink used in connection with the present invention.

Said retainer 13 as shown in Fig. 3 is provided with a sheet or like flat member 15 made of flexibly rigid, non-absorbent material such as a Bakelite or casein product or the like to cover the same for preventing an excessive direct upflow of the ink material contained in the holder. Said sheet may be rigid or semirigid so long as it allows most of the ink material in retainer 13 to creep or move laterally to the sides and then upward at any angle or vertically, eventually finding its way to the surface, instead of directly to the top of the device upon pressing of the sheet. Furthermore, sheet 15 may be substantially impervious to the ink material in order to facilitate movement of the ink material in the retainer 13 towards the ends thereof. Also, member 15 in conjunction with retainer 13 prevents the formation of smudges upon the ink transfer medium when excessive pressure is applied to remove any ink or other liquid material from the pad. Member 15, furthermore, may be provided with minute openings thru which the ink material may slowly rise to the top thereof, from retainer 13.

55 Retainer 13 and sheet number 15 are enclosed in a fabric or cloth 16 to maintain them in relatively fixed position. The cloth is preferably 55

wrapped around all the sides, and exposed top and bottom respectively of the holder and sheet so that the ink material in the holder 13 passes along the bottom 17, front 18, rear 19 and sides 5 20 and 20' to the top 21, of the cloth 16 by means of capillary or other action. The amount of ink material supplied to the top of the cloth is steady and not too abundant to cause any smudging when any ink is removed therefrom to obtain a 10 proper impression of any part of the body or any other object.

The bottom 17 of cloth 16 is retained in relatively fixed position by means of a rigid base 22 so that a compact unit is obtained and which at 15 the same time affords a smooth, unwrinkled top 21 to the cloth 16.

Said rigid base 22 is non-absorbent, being made preferably of one of the following materials, 20 namely, Bakelite, highly polished metal, hard rubber, and non-absorbent synthetic plastic materials.

Enclosing the members 13, 15, 16, and 22 is a 25 finely woven cloth 23 to insure the flow of the proper amount of ink material to the top 24. Said cloth 23 not only retains the enclosed members to remain in relatively fixed position, but also permits of the proper amount of ink material to 30 flow from holder 13 by capillary or other action, thru the fibers of cloth 16 and 23 to the top 24 thereof. The free ends of cloth 23 are retained in fixed position by means of an adhesive strip 25 made of any suitable material; such as, paper, cloth or rubber. It has been found that adhesive liquids are also effective in retaining the ends 35 of cloth 23 in fixed position. The resultant pad as above described forms a compact unit which fits snugly in holder 10 and is ready for use.

In Fig. 4, as shown, there is provided a supplemental sheet 24 inserted between the cloth 40 covers 16 and 23 respectively. The inking material in this case finds its way to the top 24 by capillary or other action of the cloth 16 and 13 to supply the desired amount of ink on the surface of the pad.

45 Instead of using a holder for ink and like material, as shown herein above, I may provide a modified form 26 as shown in Fig. 5. Said holder 26 may be made of rigid or semi-rigid material and forms in cooperation with sheet 15 a reservoir in which the ink is stored. The ink is drawn up 50 to the top of the pad by means of the capillary or other action of the cloth 16, the ends 27 of which extend thru slots or apertures 28 of the holder 26.

From the foregoing description of the present 55 invention taken in connection with the accompanying drawing, it will be noted that I have provided a novel pad for supplying a steady stream of ink material to the top thereof, for permitting fine impressions to be taken, such as of finger-

prints, hand prints, foot prints, rubber, wood, fabric or metal etchings, botanical specimens or histologic specimens. The ink is supplied from its holder to the top of the pad by a steady capillary or other action without causing any smudges to the resultant prints and the like. The ink is sufficiently spread evenly throughout the top of the pad made according to my invention, whereby fine impressions are made with the ink removed from the pad.

10 The invention as described includes the use of inks suitable for colored or colorless transfers which produce the desired color upon making the final impression. The inks may be in solution, colloidal suspension or in plastic condition as long as the same may be drawn up to the top of the pad in sufficient amount to permit efficient transfer printing.

15 It is to be further noted that the cooperative arrangement of the component parts of the pad 20 in accordance with the present invention is also dependent upon the use of a finely woven top cloth suitable for drawing the ink transfer material to the top in sufficient quantities to permit 25 formation of fine and definite impressions in the final operation of the printing or etching transfer process.

20 While the invention herein described and illustrated relates to pads, it is to be understood that modifications as to form, use of materials, 30 arrangement of parts and cooperation thereof may be made without departing from the spirit and scope of the invention as set forth and defined in the appended claim.

35 I claim:

A pad for transferable ink, comprising a container, an ink retainer in the container, a rigid non-absorbent member coextensive with the ink retainer resting on top of the retainer and adapted to inhibit the amount of ink rising upwardly from the retainer, means contacting the exterior of the retainer and the non-absorbent material for retaining said retainer and material in relatively fixed position, means within the interior of the container adapted to support the contacting means, the retainer and the non-absorbent material, and an enclosing member of fine, smooth weave for the retainer, the rigid non-absorbent member, the contacting means and the supporting means, said enclosing member having its free ends retained in fixed position in the floor of the container and being adapted to draw a steady supply of ink material from the retainer laterally thereof to the surface to permit removal of sufficient quantity of ink for forming fine delineations with said ink when used.

40 45 50 55 JOHN A. DONDERO.
